UNITED STATES PATENT OFFICE.

JORGE ESPINOSA DE LOS MONTEROS, OF MADRID, SPAIN.

LEAK-CLOSING DEVICE FOR SHIPS.

Application filed March 27, 1920. Serial No. 369,402.

To all whom it may concern:

Be it known that I, JORGE ESPINOSA DE LOS MONTEROS, a citizen of the Kingdom of Spain, residing at Madrid, in the Province of Madrid and Kingdom of Spain, have invented certain new and useful Improvements in Leak-Closing Devices for Ships, of which the following is a specification.

My invention relates to a leak closing device for ships and it has for its object to provide an improved device for stopping an inrush of water and preventing shipwreck when, for example, the ship strikes a rock or receives some similar severe shock, loosening or tearing its plates.

In accordance with this invention the apparatus comprises two main parts, one of which takes up the pressure of the water whilst the other prevents the water entering the ship.

The apparatus is illustrated by way of example in the accompanying drawings in which:

Fig. 1 shows the first mentioned part comprising a series of chains and coupling pieces;

Figs. 2 and 3 show in detail the manner in which the links of the chains are connected with each other; Fig. 2 being a longitudinal section, and Fig. 3 a transverse section;

Figs. 4, 5 and 6 are sectional details; Figs. 4 and 5 showing the engaging blocks at the ends of the links, and Fig. 6 showing the guide strap Y;

Figs. 7 and 8 are sections taken at right angles to each other and showing one of the coupling pieces between the ends of the chains;

Fig. 9 is a sectional view of a pneumatic edging which is preferably used around the fabric of the mat.

Referring to the drawings, one of the parts, which I will call the mesh, is formed of a series of chains A Fig. 1, each of which is composed of a number of links; the chains being adapted to fold in one direction and being rigid in the other directions, as will be understood from Fig. 2. Each link consists of a series of plates *a* (three or four in number) as shown at Fig. 3 and the end blocks W, W' shown at Figs. 4 and 5, and at Fig. 2. Fig. 3 is a section through the joint of a chain showing four

links *a* connected with three links *a* by the pin *a'*. Fig. 4 is a sectional view taken through the rivet hole of an end block W that fits between and over the four links *a*, and Fig. 5 is a similar view of the adjacent block W' that fits between and over the three links *a*; the rivet for securing the block W being shown at V, Fig. 2. When the device is in use the links are arranged so that they can fold only towards the ship, so that the device can conform closely to the contour of the ship's hull and thus form a rigid frame which is pressed closely against the ship by the water pressure.

The device adheres closely to the body of the ship and the chains A serve not only as a frame but also to reinforce the part of the ship that has given way.

The chains A are connected to each other by means of metal couplings, see Figs. 7 and 8 and B Fig. 1. Each of these couplings B consists of a sleeve member L having series of flanges L' extending outwardly in four directions and to which the plates *a* of the chain links are attached by suitable pins. A central pin D terminates at the side nearest the ship in the form of a head or dome part D' containing a ball E of hardened iron which is mounted upon ball bearings *e*. This arrangement facilitates the adjustment of the device along the side of the ship, the ridges formed by the overlapping of the very thickest plates, such as those used in the construction of modern ships, offering no impediment to such adjustment.

The pin D is provided with a rounded nut D' which engages and retains the pad S constituting the water resisting or staunching element. The apparatus is rolled into cylindrical shape and when a leak occurs the apparatus is placed beneath the affected part, being lowered into position and being held fast by means of cables connected with the device at N, M, Fig. 1, and passed beneath the keel of the ship.

By means of other cables connected with a rod O, P Fig. 1, fastened to the opposite edge of the device and having at R Fig. 1 ball-bearings similar to those shown at E, *e* Fig. 7, the staunching apparatus is unrolled against the ship's side and over the affected part and the leak is thus covered without difficulty.

The other main part of the apparatus

comprises a pad S, Figs. 7 and 9, composed of a cushion having two sheets of thin resilient sail-cloth with a sheet of kapok or rubber therebetween, or any other suitable material.

The pad S is made fast in the couplings B at the outer or marginal edges of the device, sufficient slackness being left to allow of the rolling up of same with the chain device.

In order to reduce the admission of water past the edges of the device, the part S is provided with a very elastic pneumatic edging (see Fig. 9) adapted to almost entirely stop the penetration of water. When the pneumatic edging is not inflated the staunching device is somewhat contracted and is thus adapted for folding up. When the device is inflated by any suitable pumping means the pneumatic tube t extends in length and stretches the pad S; the pressure of the water upon the pad ensuring the adhesion thereof to the ship's body. When the apparatus has been set in place, air is pumped into the pneumatic tube t whereupon the latter, being unable to expand in circumference, is caused to extend in length, thus carrying the edging of the pad material beyond the borders of the metallic mesh device, whilst the pressure of water ensures the close adhesion of the whole device to the ship's body.

To facilitate the sinking of the lower part of the cloth edging, the pneumatic device may be partly filled with water so that the lower part thereby loses its buoyancy, while the upper part retains it.

To prevent the possibility of the part S being pinched between two links of the chain one following on the other, these are each provided with a spring plate T, Fig. 2, which is fastened to one of the links at X, Fig. 2, and passes beneath the guide strap Y, Fig. 2 (and Fig. 6), on the end of the adjacent link.

I claim:

1. Water-staunching device for ships that have sprung a leak, comprising a resilient pad device and a frame device carrying such pad and consisting of chains jointed so that the device may fold towards the hull of the ship, and resists all folding or bending in the opposite direction and coupling devices

connecting said chains and carrying the resilient pad.

2. Water-staunching device for ships that have sprung a leak, comprising a mesh consisting of a series of chains having links connected together so that they may fold only towards the hull of the ship and are rigid in other directions, coupling devices connecting said chains and a resilient pad carried by said coupling devices.

3. Water-staunching device for ships that have sprung a leak, comprising chains adapted to fold only towards the hull of the ship, coupling devices between the chains, ball-bearing devices in the couplings for engaging the ship's hull, and a resilient pad carried by the chains for preventing the admission of water.

4. Water-staunching device for ships that have sprung a leak, comprising metal chains consisting of jointed links, means in the joints for preventing the links folding in any direction except towards the hull of the ship, coupling devices connecting such chains, and a resilient pad connected to said coupling devices for preventing the admission of water.

5. Water-staunching device for ships that have sprung a leak, comprising chains adapted to fold only towards the hull of the ship, coupling devices connecting said chains, a resilient pad carried by the said chains, and means for preventing such pad from entering between the parts of the joints in the coupling devices.

6. A water-staunching device more particularly for use in ships that have sprung a leak, comprising chains consisting of plates, end pieces, and means for connecting the plates and end pieces, a series of coupling pieces connecting the chains, a resilient pad for preventing the admission of water, means on the coupling pieces for retaining the pad and ball-bearing means on the coupling devices for engaging the hull of the ship and facilitating the handling of the device.

In testimony whereof I affix my signature,

JORGE ESPINOSA DE LOS MONTEROS.
